United States Patent Office.

JOHN PROTIN, OF NEW YORK, N. Y., ASSIGNOR TO JAMES L. HOWARD AND COMPANY, OF HARTFORD, CONNECTICUT.

Design No. 3,522, dated June 1, 1869.

DESIGN FOR A CAR-BRACKET.

The Schedule referred to in these Letters Patent and making part of the same.

To all whom it may concern:

Be it known that I, JOHN PROTIN, of New York, in the county of New York, and State of New York, have originated and designed a new Pattern for Car-Brackets, of which the following is a full, clear, and exact description, reference being had to the accompanying drawings, making part of this specification.

My invention is intended for the brackets now generally used in passenger-cars on railways, for forming baskets wherein to deposit the lighter articles of baggage.

It consists in the peculiar form and arrangement of lines, curves, and ornaments shown in the annexed drawing.

The peculiarity and novelty of my design lie in the

arrangement of the internal tracery between the curved portions *a* and *b*, and in the form and ornamentation of the right-lined portions *c* and *d*, constituting the lower part of the bracket; the arrangement and composition of the whole bracket forming a graceful and pleasing design.

Claim.

What I claim as my invention, and desire to secure by Letters Patent, is—

The design for a car-bracket, herein set forth.

JOHN PROTIN.
